COAT COMBINED WITH MUFF

Joseph Feldman, Bronx, N. Y., assignor to Scher & Feldman, Inc., New York, N. Y., a corporation of New York

Application April 22, 1952, Serial No. 283,577

4 Claims. (Cl. 2—93)

1

My present invention relates to children's coats and more particularly to a girl's coat so arranged that the front is provided with a flap secured transversely across the front and adapted selectively to be secured in an upper position across the chest to form an added wind resistant and warmth producing panel or to be rolled down and secured into a muff shaped hand warmer.

While bibs or other added panels on coats have been known, these have been for the most part internally worn or have been arranged on a vertical or diagonal seam to furnish added windbreak and warmth at the neckline. Also, while muffs as part of a garment have been known, these have been secured to the garment as a muff rather than as a multi-purpose member.

My invention contemplates a coat having a vertical opening with an added panel secured horizontally at the face of the coat. Where a single breasted closure is used, then the coat front carrying the panel is laterally extended at and below the panel so that the panel may be centralized over the opening. Buttons or other securing means are located on either side of the opening at or adjacent the neckline to support the opposite or unsecured end of the panel; the panel then covers the closure at the chest area and furnishes a windbreak or bib as well as the extra warmth derived from extra layers of cloth or other material of which the panel is made.

When the bib is rolled down, it may be fastened in rolled condition by buttons or other suitable fastening means adjacent the line of securing of the panel into a muff shape. The inner surface of the panel, when it is worn up, may be of suitable warm and/or ornamental material to form an appropriate outer surface for the muff form which occurs when the panel is rolled down. For this purpose, preferably the outer surface of the panel when it is worn up may be of the same material as the coat while the inner surface (which becomes the outer surface of the muff) may be any ornamental contrasting material such as fur or a fur simulant, velvet or contrasting cloth. Both surfaces of the panel may, of course, be, where desired, identical with each other and the coat material, may contrast with each other and the coat material or may be formed in any obvious ornamental arrangements.

The primary object of my invention, therefore, is the provision of a novel children's coat with a horizontally secured central panel adapted to be secured selectively in a chest protecting

2

closure covering position or down in a rolled muff-like appearance.

Another object of my invention is the arrangement of the panel so that, whether the panel is worn up or rolled as a muff, a regular, balanced, pleasing appearance of the garment is effected.

The foregoing and many other objects of my invention will become apparent in the following description and drawings in which:

10 Figure 1 is a front view of my novel coat with the added panel in the up, chest protecting, closure covering position.

Figure 2 is a front view of the coat of Figure 1 with the panel rolled down in muff conformation.

Figure 3 is a front view of the coat of Figures 1 and 2 prior to closing and before the panel is secured in either of the selected positions of Figures 1 and 2.

20 Figure 4 is a back view of the coat of Figures 1, 2, and 3.

Figure 5 is a partial cross-sectional view through the closed front of the coat of Figure 1 with the panel in the up position.

25 Figure 6 is a partial cross-sectional view through the closed front of the coat of Figure 2 with the panel in the muff conformation.

Figure 7 is a detail in perspective showing a removable securing for the coat panel.

Referring to the figures, the coat 10 is here shown as having a collar 11, sleeves 12, 13 and front panels 14, 15. A central closure 16 is provided for the coat with buttons 17 on panel 15 and buttonholes 18 on panel 14. Any appropriate securing means may be used at closure 16 such as a slide fastener, snaps, loops or other fastening devices.

Panel 20 is secured transversely across panel 14 by stitching 21 (see Figures 3, 4, and 5); and panel 14 is laterally extended at 14A to form a full lap closure over the lower section of panel 15. For this purpose, the edge 16A of panel 14 at closure 16 is laterally extended at 16B to form the closure edge 16C as shown in the figures (particularly Figure 3).

The stitch line 25 between panel 14 and the side of the coat then balances edge 16C of panel 14 and may, if desired, be pleated to enhance the similarity and balance of the design.

50 When the coat is closed by interengaging buttons 17 and buttonholes 18, the user then has the option of arranging panel 20 in the form of Figures 1 and 5 or in the form of Figures 2 and 6.

55 In the chest protecting closure covering form

of Figures 1 and 5, buttonholes 30, 31 of panel 20 are interengaged with buttons 32, 33 on panels 14 and 15.

In the muff form of Figures 2 and 6, the buttonholes 30, 31 of panel 20 are interengaged with button 40 on panel 14 and button 42 on panel 15 which engages also button hole 44 on panel extension 14A adjacent panel edge 16C.

The arrangement of buttons 32 and 33 and buttons 40 and 42 is such that an ornamental effect is achieved whether or not the buttons are in use.

As above pointed out, slide fasteners, snaps, loops or other fastening devices may be used in place of buttons.

Also, although in Figures 1 to 6 the panel 20 is shown sewn in place, it may be removably mounted as panel 20' of Figure 7 by slide fastener 21' or by any other releasable mounting means including buttons.

As shown, the surface of panel 20 which forms the outer surface of the muff form of Figure 2 may be made to match the collar 11. This surface may be of any desired ornamental material. Likewise, while it is preferred that the surface of panel 20 which is exposed in the form of Figure 1 match the coat material itself, this is a matter of design and contrasting materials may be used.

While my invention has here been described primarily as a girl's coat, it will be obvious that the same structure with appropriate variations in design may be utilized in coats made for infants, sub-teens, teens, juniors and misses; and that the style of coat may be varied so that the same type of structure may be utilized in storm coats, snow-suits and other types of garments. Also, while I have shown the panel as having relatively straight sides, the panel itself may have any shape required by the particular design and may, therefore, be scalloped, recessed or curved along its sides to conform to particular design considerations.

In the foregoing I have described my invention solely in connection with specific illustrative embodiments thereof. Since many variations and modifications of my invention will now be obvious to those skilled in the art, I prefer to be bound not by the specific disclosures herein contained but only by the appended claims.

I claim:

1. A coat having a pair of front panels and a closure between; the upper portion of one front panel being securable to the upper portion of the other front panel; the lower portion of said one front panel being wider than the upper portion and substantially lapping the lower portion of said other front panel; a third panel having one end secured across said one front panel at the upper end of the lower portion thereof; securement members at the upper end of the upper portion of each of said pair of front panels; and interengaging securement members at the unsecured end of the third panel; additional securement members at said one front panel adjacent the line of securement of said third panel to said one front panel; said third panel being securable selectively across the upper closure and in rolled position adjacent the line of securement of the third panel to the front panel.

2. A coat having a pair of front panels and a closure between; the upper portion of one front panel being securable to the upper portion of the other front panel; the lower portion of said one

front panel being wider than the upper portion and substantially lapping the lower portion of said other front panel; a third panel having one end secured across said one front panel at the upper end of the lower portion thereof; securement members at the upper end of the upper portion of each of said pair of front panels; and interengaging securement members at the unsecured end of the third panel; additional securement members at said one front panel adjacent the line of securement of said third panel to said one front panel; said third panel being securable selectively across the upper closure and in rolled position adjacent the line of securement of the third panel to the front panel; said third panel in the upper position having its securement members interengaged with the securement members at the upper end of each of said pair of panels; said third panel in the rolled position having its securement members interengaged with the securement members adjacent the line of securement of the third panel to said one front panel.

3. A coat having a pair of front panels and a closure between; the upper portion of one front panel being securable to the upper portion of the other front panel; the lower portion of said one front panel being wider than the upper portion and substantially lapping the lower portion of said other front panel; a third panel having one end secured across said one front panel at the upper end of the lower portion thereof; securement members at the upper end of the upper portion of each of said pair of front panels; and interengaging securement members at the unsecured end of the third panel; additional securement members at said one front panel adjacent and below the line of securement of said third panel to said one front panel; said third panel being securable selectively across the upper closure and in rolled position adjacent the line of securement of the third panel to the front panel.

4. A coat having a pair of front panels and a closure between; the upper portion of one front panel being securable to the upper portion of the other front panel; the lower portion of said one front panel being wider than the upper portion and substantially lapping the lower portion of said other front panel; a third panel having one end secured across said one front panel at the upper end of the lower portion thereof; securement members at the upper end of the upper portion of each of said pair of front panels; and interengaging securement members at the unsecured end of the third panel; additional securement members on said coat adjacent the line of securement of said third panel to said one front panel; said third panel being securable selectively across the upper closure and in rolled position adjacent the line of securement of the third panel.

JOSEPH FELDMAN.
